ATTORNEY

UNITED STATES PATENT OFFICE.

WILLIAM A. WILT, OF TYRONE, PENNSYLVANIA.

SWITCH.

Application filed February 12, 1923. Serial No. 618,686.

To all whom it may concern:

Be it known that I, WILLIAM A. WILT, a citizen of the United States, residing at Tyrone, in the county of Blair and State of Pennsylvania, have invented new and useful Improvements in Switches, of which the following is a specification.

In single track railway systems, when a freight or local enters a siding to make way for a through train, the flagman telephones from a booth arranged at one side of the switch to the signal station nearest the approach of the through train so that information can be given the engineer of such train that the track is free and he has the right-of-way. It not unfrequently happens that the flagman, after opening the switch to the siding fails to close the switch, with the result that the through train runs on to the siding and collides with the train halted therein. In other instances, it has been found that the switch has not been fully thrown to open the main line which has resulted in disasters to the through train.

The object of this invention is to provide a simple, cheap and effective means controlled by the switch for making the telephone circuit at the point opposite the switch when the switch is thrown to open the main line and for breaking such circuit when the switch is thrown to open the siding.

The invention further resides in other features of construction and in the combination and operative arrangement of elements to be hereinafter fully described, illustrated in the accompanying drawings and specifically pointed out in the appended claim.

In describing the invention in detail, reference is to be had to the accompanying drawings wherein like characters denote like or corresponding parts throughout the several views, and in which:—

Figure 1 is a plan view showing a switch between the main and siding rails of a railway system and a telephone booth located at one side of the switch.

Figure 2 is a sectional view on the line 2—2 of Figure 1, showing the position of the circuit breaker when the switch is thrown to open the siding.

Figure 3 is a similar sectional view but showing the position of the circuit breaker when the switch is thrown to open the main line.

Referring now to the drawings in detail, the numeral 1 designates the main and 2 the

siding track of a railway system. Between the rails of the main and siding there is the usual switch 3 having its points connected by a bridle bar to a throw rod 4. The throw rod is operated in the usual manner by a weighted lever. At one side of the switch there is a telephone booth 5. The wires from the telephone 6, in the present instance, lead directly to a circuit breaker 7 and from thence to signal stations nearest the switch.

Ordinarily, when a freight train enters the siding to make way for a through train the switch is thrown to open the main line, and the flagman of the freight train enters the booth and telephones to the signal station that his train is in the siding and that the main line is free for the through train.

As previously stated, it has occurred when the flagman, before sending his message, forgets to throw the switch to open the main line, and in other instances the switch has not been fully thrown to open the main line. Therefore I have, in the present instance either elongated or connected to the switch throw rod 4 an extension whose free end is pivotally secured to a bell crank lever 8 disposed below the circuit breaker 7. The bell crank lever has connected to its second arm a rod 9 which in turn is connected to the slidable element of the switch that constitutes the sliding element of the circuit breaker. The throw rod 4, and the bell crank lever 8 are so proportioned that the switch must be fully thrown to open and closed position before the telephone circuit is made or broken, and when the circuit is broken, it is impossible to use the telephone.

This serves to notify the flagman that he has either neglected to return the switch to open the main line after his train has entered the siding, or that the switch is not fully thrown, so that accidents which occur from such contingencies will be effectively overcome.

It is thought from the foregoing description that the advantages and novel features of the invention will be readily apparent.

I desire it to be understood that I may make such changes in the combination and arrangement of parts as fall within the scope of what I claim.

Having described the invention, I claim:

The combination with a pair of switch points and an operating rod connected there-

with and extended horizontally and at right angles to the switch points, a weighted operating element pivotally connected with the rod intermediate its ends, a bell crank lever 5 pivoted to swing about a horizontal axis and pivotally connected with one end of the rod, a pair of fixed contacts, adapted to be connected with an electrical circuit, and a pair of vertically movable contacts pivot- 10 ally connected with the bell crank lever and

adapted to engage the fixed contacts to complete said circuit when the switch is in operative position, the weighted operating element serving to hold the movable contacts into positive engagement with the fixed contacts until the operating elements are swung to normal position. 15

In testimony whereof I affix my signature.

WILLIAM A. WILT.
